UNITED STATES PATENT OFFICE.

CLARENCE C. STIRLING, OF HARTFORD, CONNECTICUT, ASSIGNOR TO THE HART & HEGEMAN MANUFACTURING COMPANY, OF HARTFORD, CONNECTICUT, A CORPORATION OF CONNECTICUT.

ELECTRIC SWITCH.

1,278,780.

Specification of Letters Patent. Patented Sept. 10, 1918.

Application filed January 11, 1918. Serial No. 211,443.

To all whom it may concern:

Be it known that I, CLARENCE C. STIRLING, a citizen of the United States, residing at Hartford, in the county of Hartford and State of Connecticut, have invented certain new and useful Improvements in Electric Switches, of which the following is a specification.

This invention relates to electric switches. 10 The invention may be incorporated in switches of various styles. It is of particular advantage, however, when incorporated in what is known as a "pendent snap switch." One of the primary purposes I 15 have in view is the provision of a structure which is exceedingly compact and which can be readily and easily snapped between on and off positions.

In the drawings accompanying and forming part of the present specification I have shown in detail a form of embodiment of the invention which I will set forth fully in the following description to enable those skilled in the art to practise the invention. I am 25 not necessarily restricted to this particular disclosure; I may depart therefrom in several respects within the scope of the invention defined by the claims following said description.

80 Referring to said drawings:

Figure 1 is an elevation of a switch comprising the invention.

Fig. 2 is a vertical sectional view of the same, the section being from front to rear.

Fig. 3 is a section on the line 3-3 of Fig. 2, looking in the direction of the arrows.

Fig. 4 is a horizontal section on the line 4-4 of Fig. 2, also looking in the direction 45 of the arrows.

Like characters refer to like parts throughout the several views.

The switch comprises in its construction a suitable supporting body generally made of insulating material such as porcelain or vulcanized rubber. The body shown is denoted in a general way by 2 and it is practically of cylindrical shape. It fits within a shell as 3 generally of sheet metal, the shell being practically of bell form and receiving comparatively closely within it the insulating supporting body 2. The lower edges of the parts mentioned are ordinarily flush; said parts may be united in any de-

sirable manner. As a matter of advantage 55 a single element such as the pin 4 is shown for this purpose, this pin being usually driven through registering openings in the two parts. The pin in addition to connecting the body and shell also as will herein-after appear presents a suitable pivot for an actuator for a switching member. The supporting body has diametrically opposite slots as 5 and 6 which extend for the major part of the depth or height of the supporting body. The material of the supporting body between the two slots 5 and 6 at the top presents the maximum diameter of the supporting body and is contiguous to the inner surface of the inclosing shell 3. To 70 the bottoms of the two slots 5 and 6 are suitably fastened the shanks of the contact members 7 and 8, screws as 9 being provided to hold the contact members in place. The contact members above the screws as shown 75 are extended inward and are then prolonged upward to act as the complementary contacts 10. The contacts 10 as well as the inwardly prolonged portions of the connecting and contact members 7 and 8 are obviously resilient or springy. When the switch is "on" the switching member to be hereinafter described, is between these contacts 10. The wires 11 pass through an insulated bushed opening 12 in the top of the shell 3 and their 80 bared ends are coiled about the shanks of the two screws 9. The supporting body 2 has a diametrical slot 13 into which the cylindrical seats 14 open. These seats 14 receive for rocking motion the cylindrical rocker 15. The seats 14 in fact intersect the opening 16, the upper portion 17 of the wall of which is on a flare or downward or inward taper, diametrically opposite parts of this flared portion acting as stops for a switching member 85 such as that denoted in a general way by 18. The rocker 15 has a transverse central perforation 19 to receive the shank 20 of the switching member, this shank being slidable through the perforation. The shank 20 has 100 at its upper end the head 21 and at its lower end the foot 22. The shank 20 is also surrounded by the coiled spring 23, the lower end of which bears against the foot 22 and the upper end of which bears against the 105 rocker 15, this spring generally being under compression at all times.

The actuator for the switching member

is denoted in a general way by 24. It comprises a body as 25 preferably made of insulating material such as vulcanized rubber. This oscillating body 25 is supported practically centrally of its length by the pin 4 to which I have already referred. It will, therefore, be clear that the insulating body of the actuator can rock on the pin. Said body 25 is fitted in the slot 13 and at all 10 times either one end or the other projects from the slot. It is equipped with the buttons 26 and 27 presenting a convenient means for obtaining the necessary oscillation of the body. Other means might conceivably be provided for this purpose; as a matter of fact in some cases the buttons might be omitted and the body 25 directly manipulated. Said body has on its inner side the arcuate controlling surface 28 which 20 is in the construction shown the means by which the circuit controlling or switching member 18 is operated; that is moved between the "on" and the "off" positions.

In Fig. 3 the full lines show the parts as 25 "off," it being clear that the foot 22 is at all times contiguous to the arcuate or concaved surface 28. The foot 22 is shown in fact near the left end of the said face. To effect the closed circuit relation the following 30 action may be adopted: The button 26 will be pushed upward, thus rocking the actuator toward the dotted line position. This particular motion of the actuator causes the core or pin to move upward, and at the same 35 time traverse the arcuate face 28 toward the right in Fig. 3. This action will continue, the result being the further compression of the spring 23 as the foot rides along the face 28. There will be an instant when this 40 face will release the foot 22, and as a consequence the switching member 18. When the switching member is released the coiled spring 23 then under maximum compression will react and thus swing over the switching 45 member 18, so that the portion 21 will be projected automatically between the two contacts 10. To open the switch the action described will be reversed.

What I claim is:

50 1. A switch comprising a supporting body provided with contacts, a rocker supported by the body, a shank freely extending through the rocker and having a head and a foot at opposite sides of the rocker, and the head when the switch is "on" being adapted to engage said contacts, a coiled spring, the spring acting against the rocker and against the foot portion of the shank, and an oscillatory actuator having a face 55 engageable by the foot, the actuator as it oscillates being adapted to cause the foot to traverse said controlling face and thus compress the spring, the actuator when it is moved a certain distance freeing the foot and therefore the shank to cause the spring 60

by reaction to oscillate the shank and therefore the rocker to move said head to the "off" relation.

2. A switch comprising a supporting body provided with contacts, a rocker supported by the body, a shank freely extending through the rocker and having a head and a foot at opposite sides of the rocker, the head when the switch is "on" being adapted to engage said contacts, a coiled spring around the shank acting against the rocker and against the foot portion of the shank, and an oscillatory actuator having a face engageable by the foot, the actuator as it oscillates being adapted to cause the foot to traverse said controlling face and thus compress the spring, the actuator when it is moved a certain distance freeing the foot and therefore the shank to cause the spring by reaction to oscillate the shank and therefore the rocker to move said head to the "off" relation, the rocker being provided with buttons secured to it at opposite sides of its center of motion.

3. A switch comprising a supporting body provided with contacts, a rocker in the body, a shank freely extending through the rocker and having a head and a foot at opposite sides of the rocker, spring means acting against the rocker and the foot, and an oscillatory actuator having a controlling face engageable by the foot, the actuator as it is oscillated being adapted to cause the foot to traverse said controlling face and to release the foot and therefore the shank when it has traveled a certain distance, the spring means when the foot is thus released acting to impart a snap movement to the shank and therefore the rocker for thus causing the movement of the head to "on" and "off" 105 positions alternately.

4. A switch comprising a supporting body provided interiorly thereof with contacts, a rocker in the body, a shank freely extending through the rocker and having a head and a foot at opposite sides of the rocker, a coiled spring around the shank acting against the rocker and against the foot portion of the shank, and an oscillatory actuator mounted within and extending from the body, the actuator having a controlling face engageable by the foot, the actuator as it is oscillated being adapted to cause the foot to traverse said controlling face and thus compress the spring, the actuator when moved a certain distance freeing the foot and therefore the shank to cause the spring by reaction to oscillate the shank and thus the rocker to cause the head to alternately move between the "on" and the "off" positions.

5. A switch comprising a supporting body provided with contacts, a rocker in the body, a shank freely extending through the rocker and having a head and a foot at opposite 130

sides of the rocker, the head being adapted to engage the contacts when the switch is in the "on" relation, a coiled spring around the shank acting against the rocker and against the foot portion of the shank, and an oscillatory actuator having an arcuate face on its inner side engageable by the foot, the actuator as it is oscillated being adapted to cause the foot to traverse said face and thus 5 compress the spring, the actuator when moved a certain distance freeing the foot and therefore the shank to cause the spring by reaction to oscillate the rocker and thus move said head alternately between "on" 10 and "off" positions.

6. A switch comprising an insulating supporting body, a shell within which the body is disposed, a pin uniting the shell and the body, an actuator supported within the 15 body by the pin, and a switching member supported by and within the body, and

means within the body to cause snap movements of the switching member between "on" and "off" positions by and on the movement of the actuator.

25

7. A switch comprising an insulating supporting body, a bell-like shell within which the body is disposed, a single pin uniting the shell and the body, an actuator supported for oscillation by the pin within the 30 body, and switching means carried by the body within the same, and means within the body to cause snap movements of the switching member between "on" and "off" 35 positions by and on the movement of the actuator.

In testimony whereof I affix my signature in the presence of two witnesses.

CLARENCE C. STIRLING.
